UNITED STATES PATENT OFFICE.

ETHAN L. DODDS, OF PITTSBURGH, PENNSYLVANIA, ASSIGNEE TO UNION METAL PRODUCTS COMPANY, OF CHICAGO, ILLINOIS, A CORPORATION OF DELAWARE.

CAR PART.

Application filed July 16, 1923. Serial No. 651,905.

This invention relates to improvements in car parts and more particularly to such as are adaptable for use in forming ends, sides, roof or door sheets for metal railway cars.

5 Car ends or side sheets as heretofore constructed have been subjected to strain which has caused them to become more or less distorted before they finally assume a condition which will constitute their elastic limit, in 10 which condition they will serve to a greater or less extent to sustain the load which they are intended to carry.

One object of my present invention is to so form a car part or sheet that it shall, in its 15 manufacture, be made to assume the condition which car sheets as heretofore constructed have had to assume after initial use in service, and thus to provide a car sheet or part which, at the very beginning of its use 20 in a car shall be capable of sustaining the load without distortion to bring it to the limit of its elastic displacement.

A further object is to so form a sheet having the characteristics above mentioned that 25 the metal of the sheet shall not be weakened in any way and to shape the sheet in such manner that its load-sustaining property thereof shall be enhanced.

With these and other objects in view, the 30 invention consists in certain novel features of construction and combinations of parts as hereinafter set forth and pointed out in the claims.

In the accompanying drawings,—

35 Figure 1 is a face view of a sheet or sheet section embodying my invention.

Figure 2 is an edge view of the same.

Figure 3 is an end view.

40 Figure 4 is a perspective view of an elongated sheet or section showing a slight modification of the construction illustrated in Figure 1.

Figure 5 is a face view illustrating two sheet sections united by welding, and

45 Figure 6 is a similar view showing sheet sections united by riveting.

In the embodiment of the invention the metal is pressed, either hot or cold, in suitable dies so that its central portion may be so bulged as to form inclined faces 1—2 and inclined triangular faces or walls 4—5. The wall portions 1, 2, meet along the longitudinal center of the sheet and may approximately merge at their side edges into the side 55 edges of the sheet. The triangular end walls

4—5 may be approximately coincident with the end edges of the sheet and their apices meet the ends of the apex 6 formed by the two longitudinal inclined walls 1 and 2. The ends of the sheet may be provided with 60 flanges 8, and these flanges may have suitable rivet or bolt holes 9. I prefer however not to provide the side edges of the sheet with flanges and the rivet holes will preferably be located along or near the side edges of the 65 sheet as indicated at 10, Figure 1. The side edges of the inclined walls 1 and 2 will be made to terminate somewhat inwardly from the side edges of the sheet and the rivet holes may be located between the side edges of the 70 sheets and the side edges of the walls 1—2.

When a car end or side is made in sections, the side edge portions of the sheets or sections will not be flanged with the possible exception of the upper edge of the upper 75 sheet section and in some cases it might be desirable to flange the lower edge of the lower section.

In assembling the sheet sections to form a car end or side, the sections will be made to overlap at adjacent edge portions and these overlapping portions of the sheet sections may be secured together by riveting, as indicated at 13, Figure 6, or they may be made plain or without rivet holes and the overlapping edge portions welded together, as indicated at 14 Figure 5.

Having fully described my invention what I claim as new and desire to secure by Letters Patent, is:

1. In combination with the other elements of a railway car, an end wall therefor made of a metallic sheet having its central portion embossed to form flat surrounding margins, said embossed portion comprising oppositely disposed inclined longitudinal walls forming a ridge and triangular inclined end walls having their apices meeting said ridge and their bases merging into said margins.

2. In combination with the other elements of a railway car, an end wall therefor made of a metallic sheet having its central portion embossed to form flat surrounding margins, the margins at the opposite ends being bent to form perpendicular flanges, said embossed portion comprising oppositely disposed inclined longitudinal walls forming a ridge and triangular inclined end walls having their apices meeting said ridge and their bases merging into said margins.

3. In combination with the other elements of a railway car, an end wall therefor made of a plurality of metallic sheets each having their central portion embossed to form flat surrounding margins which are secured to the margins of the adjacent sheet, said embossed portion comprising oppositely disposed inclined longitudinal walls forming ridges and triangular inclined end walls having their apices meeting said ridge and their bases merging into said margins, the distance between the ridges of adjacent sheets being substantially the same as the width of said embossed portion.
4. In combination with the other elements of a railway car, an end wall therefor made of a plurality of metallic sheets each having

their central portion embossed to form flat surrounding margins which are secured to the margins of the adjacent sheet, the margins at the opposite ends being bent to form perpendicular flanges, said embossed portion comprising oppositely disposed inclined longitudinal walls forming ridges and triangular inclined end walls having their apices meeting said ridge and their bases merging into said flange, the distance between the ridges of adjacent sheets being substantially the same as the width of said embossed portion.

In testimony whereof, I have signed this specification.

ETHAN I. DODDS.
